G. LEACH.

Grain Cleaner.

No. 12,512.

Patented March 13, 1855.

UNITED STATES PATENT OFFICE.

GEORGE LEACH, OF OWEGO, NEW YORK.

GRAIN-CLEANER.

Specification of Letters Patent No. 12,512, dated March 13, 1855.

To all whom it may concern:

Be it known that I, GEORGE LEACH, of Owego, in the county of Tioga and State of New York, have invented a new and Improved Machine for Cleaning Grain; and I do hereby declare that the following is a full, clear, and exact description of the same, reference being had to the annexed drawings, making a part of this specification, in 10 which—

Figure 1 is a vertical section of my improved machine the plane of section being through the center. Fig. 2 is also a vertical section of do., the plane of section being 15 through the blast spout a short distance from the center of the machine but parallel with the plane of section of Fig. 1. Fig. 3 is a face view of the under or bed stone. Fig. 4 is a face view of the top stone or 20 runner.

Similar letters of reference indicate corresponding parts in the several figures.

This invention relates to a new and improved machine for cleaning grain, and 25 consists in dressing or furrowing the stones in a peculiar manner as will be hereafter fully shown and described.

To enable others skilled in the art to fully understand and construct my invention, I 30 will proceed to describe it.

A represents a suitable frame work constructed in any proper manner to support the several parts of the machine.

B represents a bed stone and C is the 35 runner. The bed stone B is permanently secured on the upper part of the frame work A and a spindle D runs through its center as usual, the lower end of said spindle being stepped in a bridge tree E, which is adjusted by a screw rod F.

The spindle D has a driver G on its upper part which is in the form of a cross, or it may be described as having four arms (a) 40 see Fig. 3, which project radially from a boss or hub (b) which fits in the spindle D.

The eye of the runner C has a metal tube H fitted within it and at the lower end of this tube there are four sockets (c) which correspond to the arms (a) of the driver 45 and in which sockets the arms (a) fit when the runner is adjusted over the bed stone B, see Fig. 1. Through each socket (c) there is a vertical set screw (d) as shown in Figs. 1 and 4.

The face of the bed stone B has four

grooves or furrows (e) cut in it tangential with the center hole through which the spindle D passes. The grooves or furrows (e) extend outward about half way between the spindle and periphery of the stone see 60 Fig. 3. At the edge of the face of the stone there are four grooves or furrows (f) which are somewhat curved and extend inward nearly half way to the spindle D.

The face of the runner C, has four grooves 65 or furrows (g) cut in it, which are also curved and extend from the edge of the runner about half way to the eye of the runner see Fig. 4. Between these grooves or furrows (g) there are grooves or furrows (h) which are curved from the edge of the runner to points (i) near the eye and from the points (i) to the eye or tube H the grooves or furrows are tangential with the eye or tube H. Around the stones B, C, 70 there is a curb I formed of perforated metal or wire cloth see Figs. 1 and 2.

On the lower part of the frame work A at one side there is a fan box J, see Figs. 1 and 2, which incloses a fan K, see Fig. 2, 80 and L is a horizontal spout which communicates with the fan box J. The spout L communicates with the lower part of a vertical spout M having a screen N over its upper end and a slide O which works over an 85 opening P in the upper part of the spout M at its outer side. Q is a hopper on the upper part or top of the curb I.

R is a driving pulley on the fan shaft S and T represents a cone of pulleys on the 90 spindle D. U is a spout leading from the stones B, C, to the spout M.

The grain to be cleaned is placed in the hopper Q and motion is given to the runner C and fan K. The grain passes down between the two stones B, C. The tangential portions of the grooves or furrows (h) in the face of the runner C and the tangential grooves or furrows (e) in the face of the bed stone B, keep the eye clear or free as they conduct the grain quickly toward the edges of the stones, while the curved portions of the grooves or furrows (g) and grooves or furrows (f) in the bed stone retard the passage of the grain outward so that it cannot pass too quickly through or between the stones. The stones are not placed very closely together as it is designed that the grain shall be scoured or rubbed endwise by the stones, for the purpose of 100 105 110

taking out the eyes of the grain, and scouring off the fuzz that is attached to the ends of the grain.

The stones are adjusted the proper distance apart by raising or lowering the bridge tree E by means of the screw rod F. The parallelism of the two stones is preserved by adjusting the set screw (d) in the sockets (c) as these set screws rest upon the arms (a). The dust that is scoured off the grain passes through the perforated or wire cloth curb I.

The grain after passing between the stones B, C, falls through the spout U into the spout M and the blast generated by the fan K forces out the dust, chaff, ches and other light impurities through the opening P while the sound grain by its superior gravity falls through the blast and passes out at the lower end of the spout M. The screen N prevents the lighter sound grain from passing out at the top of the spout M, the grain striking it and rebounding backward and falling down the spout M. The black ar-

rows Fig. 2 show the direction of the blast and the red arrows show the direction of the sound grain.

The above machine cleans wheat effectively of smut and deprives the grains of wheat of their eyes, which cause the flour to be speckled with fine yellowish spots. It will also hull rice, and clean buckwheat perfectly.

Having thus described my invention what I claim as new and desire to secure by Letters Patent, is,

Dressing or furrowing the stones by having the furrows or grooves (e) (f) cut in the face of the bed stone B, and the furrows or grooves (g) (h) in the face of the runner C, said furrows or grooves being of the form or shape as herein shown and described and for the purpose as set forth.

GEORGE LEACH.
